CLAIM

The ornamental design for a meat smoker firebox as shown and described.

DESCRIPTION

FIG. 1 is a top, side perspective view of a meat smoker firebox showing our new design in an environment of use; FIG. 2 is a front elevation view of the meat smoker firebox; FIG. 3 is back side, elevation view of the meat smoker firebox;

FIG. 4 is a right-side elevation view of the meat smoker firebox;

FIG. 5 is a left-side elevation view of the meat smoker firebox;

FIG. 6 is a top plan view of the meat smoker firebox; and, FIG. 7 is a bottom plan view of the meat smoker firebox. The broken lines in the figures showing a meat smoker illustrate environment and form no part of the claimed design.
